UNITED STATES PATENT OFFICE.

WALTER I. SMITH, OF BROOKLYN, AND ALGERNON R. BURNETTE, OF NEW YORK, N. Y.

METHOD OF CLEANING TUNNELS, SUBWAYS, OR THE LIKE.

Application filed April 25, 1921. Serial No. 464,136.

To all whom it may concern:

Be it known that we, WALTER I. SMITH and ALGERNON R. BURNETTE, citizens of the United States, and residents, respectively, 5 of the city of New York, borough of Brooklyn, in the county of Kings and State of New York, and of the city of New York, borough of Manhattan, in the county and State of New York, have invented a new 10 and Improved Method of Cleaning Tunnels, Subways, or the like, of which the following is a full, clear, and exact description.

This invention relates to a method of 15 cleaning tunnels, subways, underground railways, or the like, and refers more particularly to a method of accomplishing the same by means of air.

The invention contemplates for one of its 20 principal objects a method of this character by which subways, tunnels and the like may be thoroughly, efficiently and expeditiously cleaned of refuse, papers, dust, dirt or other extraneous matter which collects therein.

As a further object the invention contemplates a method which in addition to 25 cleaning a tunnel, subway or the like and removing therefrom the refuse and other extraneous matter, effects the washing, filtering and purifying of the air and a redistribution of said purified air.

With the above recited and other objects 30 in view, which will appear more clearly as the nature, purpose and use of the method is better understood, reference is had to the following specification, the appended claims and the accompanying drawings in which one embodiment of an apparatus for carrying the method into practice has been illustrated.

40 In the drawings—

Figure 1 is a sectional plan view of a car in which the apparatus is installed.

Fig. 2 is a longitudinal sectional view therethrough taken approximately on the 45 line *a—a* of Fig. 1.

Fig. 1^a is a sectional plan view of a trailer adapted to be connected to the car illustrated in Fig. 1 and representing a continuation of Fig. 1.

50 Fig. 2^a is a longitudinal sectional view on the line *b—b* of Fig. 1^a.

Referring to the drawings by character of reference, the apparatus here illustrated as one means of carrying the method into practice consists of a car 10 which may be either drawn or which may include self-contained

means for driving the same. Where the method is employed for cleaning subways, railway tunnels or other forms of underground railways, the car is designed to operate for movement over the tracks 11 in the usual manner and is provided with supporting and driving trucks 12. The cleaning apparatus comprises essentially a plurality of nozzles 13 arranged to expel a 60 draft of air outwardly from all sides of the car laterally with respect to the path of travel for the purpose of loosening and stirring up the refuse, dirt, dust or other extraneous matter which collects on the road 65 bed, sides and top constituting the walls of the tunnel or subway. Preferably two series of outlet nozzles 13 are employed and the same are longitudinally spaced apart as illustrated. This draft of air is projected 70 forcibly from the nozzles by means of any suitable form of air blower 14 which is respectively connected thereto by a conduit 15, having branch pipes 16 and 16^a leading to each series of nozzles, a suitable damper 75 17 being provided for selectively directing the draft to the other series of nozzles. A series of inlet nozzles 18 are arranged between the two series of outlet nozzles 13, the said inlet nozzles being connected to an 80 air suction device 19. The outlet of the air suction device is connected to a conduit 20 which leads through a flexible connecting conduit 21 to the interior of a closed trailer 22. The trailer is provided with a separating screen 23 and a return compartment 24 having communication with the closed trailer at the opposite side of the screen to that side with which the flexible conduit 21 communicates. The compartment 24 is 85 connected by a return flexible conduit 25 to the intake end 26 of an air washing or filtering apparatus 27, and the outlet end of said apparatus 27 is connected by a conduit 28 to the intake of the air blower 14. 90

In operation that series of outlet nozzles which are in advance of the inlet nozzles according to the direction of travel of the car are active, while that in rear is inactive, the damper 17 being shifted for this purpose. It necessarily follows that as the car is moved, the forced air blower 14 will project a film of air from all sides of the car transversely to the movement of the same to stir up and loosen the refuse, dirt, dust 105 or other extraneous matter which adheres to the road bed, sides and top of the tunnel 110

or subway, and the intake nozzles 18 through their communication with the suction device 19 will create a suction film transversely to the path of travel or movement of the car to gather up and collect said extraneous matter which will be forced from the outlet of said suction device through the conduits 20 and 21 into the trailer 22 where the larger and heavier particles will be separated from the air and smaller particles by the screen 23. The air laden with the remaining smaller and lighter particles will be forced and drawn through the return conduit 25 into the intake 26 of the air washer or filter 27 where the impurities and extraneous matter will be removed therefrom and the purified air drawn therefrom through the pipe 28 by the action of the forced air blower 14 through the intake of said blower and expelled therefrom through the outlet nozzles.

From the foregoing it follows that the method of cleaning subways, tunnels, or other similar structures consists essentially in stirring up and putting to flight the refuse or other extraneous matter by means of a forced air blast or draft expelled radially or transversely against all of the walls of the tunnel or subway while moving the same axially or longitudinally thereof, and gathering up the refuse or extraneous matter while stirred up or in flight by a suction air current operating simultaneously on all of the walls of the tunnel and moving longitudinally therethrough in rear of the air blast or draft whereby the suction constitutes a barrier for preventing the possible passage of the dislodged refuse or extraneous matter into the previously cleaned portion of the tunnel in rear of said suction film.

The method may also include the removal of polluted air simultaneously with the removal of the extraneous matter, the separation of the heavier and larger particles therefrom, the washing or filtering of the air to remove the residue of the lighter and smaller particles of the extraneous matter to purify the same and the redistribution of the purified air simultaneously with the operation of stirring up the extraneous matter by the forced air blast or draft.

It is to be understood that the method is

subject to slight variations in the steps set forth herein, to the full extent indicated by the general meaning in which the terms are expressed and by variations in the phrasing of the same.

Having thus described our invention, what we claim is:

1. The herein described method of cleaning tunnels, subways, or other similar structures, consisting in simultaneously moving axially through said structure longitudinally spaced films of air blast and suction, the said air blast film being directed against all of the walls of the structure and serving to dislodge and put to flight the extraneous matter in advance of the suction film, the said suction film operating to gather up the extraneous matter while dislodged and in flight and at the same time constituting a barrier for preventing the possible passage of the dislodged matter behind the same and into the previously cleaned portion of the tunnel.

2. The herein described method of cleaning tunnels, subways or other similar structures of this character, consisting in first dislodging from the walls of the structure and putting into flight the extraneous matter thereon by means of an air blast directed transversely against all of the walls of the tunnel and moved progressively throughout its length, and then gathering up said extraneous matter while dislodged and in flight by a suction air current moved progressively through the tunnel in rear of the air blast and simultaneously therewith.

3. The herein described method of cleaning tunnels, subways or other similar structures of this character, consisting in first dislodging from the walls of the structure and putting into flight the extraneous matter thereon by means of an air blast directed transversely against all of the walls of the tunnel and moved progressively throughout its length, gathering up said extraneous matter while dislodged and in flight by a suction air current moved progressively through the tunnel in rear of the air blast and simultaneously therewith, purifying the suction air current, and discharging the same.

WALTER I. SMITH.
ALGERNON R. BURNETTE.
